Letters Patent No. 3177 Dated Oct 10-1865

Design for a Hat.

The schedule referred to in these letters Patent and making party of the same.

Seal whom it may concern:

Be it known that we, D. K. Albright of Philadelphia, Pennsylvania, and S. H. De Langes of Boundertown New Jersey, have invented or produced a new and original design for a hat, and we do hereby declare the accompanying drawing with the following explanation of the same, to form a full, clear and exact description of the said design.

In the accompanying drawing,

Represents the body of the hat, and the brim.

The body of the hat gradually increases in diameter from the point y. to the point z, from which to the point where it meets the brim, it is of the same diameter, an enlargement of the character shown in the drawing being thus formed.

We claim,

The shape and configuration, substantially as illustrated in and by the accompanying drawing, of the hat, between the body and the brim.

For testimony whereof we have signed our names.

To this specification in the presence of two subscribing witnesses.
